INCENDIARY BULLET

William E. Blackdorn, Hartford, Conn., and
Richard N. Nelson, Black River Falls, Wis.

Application June 27, 1941, Serial No. 400,041

3 Claims. (Cl. 102—30)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to incendiary bullets.

In the employment of incendiary bullets it has sometimes occurred that the bullet would be fired into material where a deficiency of oxygen allowed the incendiary material to be smothered before it had done its effective work.

It is, therefore, an object of this invention to provide an incendiary bullet which carries a sufficient amount of oxygen to insure complete and effective combustion.

It is a further object of this invention to provide an incendiary bullet of simple construction which will be highly effective under all conditions.

The specific nature of the invention as well as other objects and advantages thereof will clearly appear from a description of a preferred embodiment as shown in the accompanying drawing in which:

Figures 1 and 2 are longitudinal cross sections showing two modifications of our invention.

Figure 3 is a cross section taken on the line 3—3 of Figure 1.

Referring to the drawing by characters of reference, Figure 1 shows an incendiary bullet with a point section 1 having a chamber 2 open at its rear end formed therein. A groove 3 and a rearwardly facing shoulder 4 are formed on the exterior of the point section to cooperate with the jacket 5 as will hereinafter appear. Fitted in the chamber 2, and extending slightly to the rear thereof, is a bulb 6 of readily shatterable material having compressed oxygen or oxygen-producing material 7 contained therein. A cup-shaped jacket 5 of gilding metal or the like, has its base portion filled with finely divided metallic titanium 8 or other and highly combustible material. Flash passages 9 in the walls of the jacket are sealed with plugs of an alloy having a low fusion temperature. A plug 10 of this alloy seals the jacket in front of the incendiary charge, and the jacket is fitted over the reduced rear end of the point section. A recess 11 in the plug 10 is provided to accommodate the rear end of the oxygen bulb. The forward end of the jacket is seated against the shoulder 4 and the jacket may be crimped into the groove 3 to secure the point section to the jacket. Alternatively the jacket may be crimped to the point section and the plug of fusible alloy cast in place.

Upon firing the heat developed by the pro-

pellent charge and by friction in the passage of the bullet through the bore and the air will be sufficient to cause fusion of the alloy forming the sealing plugs and the material will be thrown out by centrifugal force. Upon impact the bulb containing the compressed oxygen will be shattered and the oxygen released. The projectile which has been heated in firing and flight will be further heated on impact to the ignition temperature of the incendiary charge which burns vigorously in an oxygen atmosphere. The excess of oxygen provided ensures that combustion will take place and be imparted to the surrounding medium regardless of the absence of oxygen in the medium entered. For example if the projectile should be ignited on striking a gasoline tank or the like the combustion might, in the absence of a self-contained oxygen supply, be extinguished in the interior of the tank before its purpose has been accomplished.

In the modification of the invention shown in Figure 2 the jacket 12 is provided in its front portion with an axial threaded opening 13 in which an ogival nose portion 14 may be engaged. A plurality of flash passages 15 are formed in the wall of the jacket communicating with the interior thereof. The flash passages are closed by a low fusible alloy and a disk 16 of the same material fills the end of the jacket. Seated against the fusible alloy disk is a bulb 6 of shatterable material having compressed oxygen 7 therein. Surrounding the oxygen bulb 6 is a charge 8 of metallic titanium or other and highly combustible material. A plug 11 closes the base of the jacket and the rim 18 of the jacket is crimped thereover to complete the seal.

This modification functions as does that in Figure 1 in that the fusible alloy melts and is disposed of in flight. Upon impact the oxygen is released and the incendiary charge bursts into violent combustion imparting the flame to the surrounding medium. The disks 16 and 10 provide a cushioning effect for the capsule 6 to guard against shocks of ordinary handling.

We claim:

1. An incendiary projectile comprising an ogival point member having a chamber therein communicating with the rear end of said point member, a shatterable bulb in said chamber, compressed oxygen in said bulb, a cup-shaped jacket having its open end secured to the rear portion of said point member, an incendiary charge in the base of said jacket and spaced from said point member, flash passages in said jacket; and a low fusible alloy sealing said flash passages and occu-

pying the space between the incendiary charge and the point member.

2. An incendiary bullet comprising a body having means forming an axial chamber therein, said chamber terminating short of the forward end of the body, an ogival nose portion secured to said forward end of the body, means forming passages in said body communicating with said chamber near the forward end, a low fusible alloy in the forward end of said chamber and sealing said passages, a bulb of shatterable material in said chamber adjacent said alloy, compressed oxygen in said bulb, an incendiary charge in said

chamber partially surrounding said bulb, and means closing the rear end of said body.

3. An incendiary projectile comprising an ogival point member having a chamber therein communicating with the rear end of said point member, a shatterable bulb in said chamber, compressed gaseous oxidizing material in said bulb, a hollow rear member attached to said point member and incendiary material in said rear member.
